EDWARD L. STEVENS, OF HOULTON, MAINE, ASSIGNOR TO ISAAC BARKER,
OF SAME PLACE.

Letters Patent No. 79,273, dated June 23, 1868.

IMPROVEMENT IN SLED.

The Schedule referred to in these Letters Patent and making part of the same.

TO ALL WHOM IT MAY CONCERN:

Be it known that I, EDWARD L. STEVENS, of Houlton, in the county of Aroostook, and State of Maine, have invented a new and valuable Improvement in Coasting-Sleds; and I do hereby declare that the following is a full, clear, and exact description of the construction and operation of the same, reference being had to the annexed drawings, making a part of this specification, and to the letters and figures of reference marked thereon.

Figure 1 of the drawings is a plan view of my device; and

Figure 2 is a longitudinal section thereof.

My coasting-sled is constructed in the ordinary form, with runners, knees, and the like, except that I fashion it in such manner that the attachments hereinafter mentioned may be readily adjusted thereto.

The letter A represents a rudder. This is a short runner pivoted, in the manner shown, midway between the main runners of the sled, to the forward roller or draught-beam B.

Letter C is a bell attached to the extreme front or frame of the rudder.

Letter D is a spiral spring adjusted between the draught-beam B and rudder A, and is loosely clasped around the standard E, by which the rudder is pivoted to said draught-beam.

Letter G is a bar extending rearward from the standard E to the platform of the sled. It is slotted, as represented by letter H, to allow the rudder to move back and forth. This slot H and spring D, in combination and singly, serve to aid the passage of the sled over obstructions and inequalities of ground, and especially do they aid in steering the same. By this means the rudder is allowed to work vertically with the spring and longitudinally in the slot.

The letters K are chains attached to the body of the sled, and the ends, respectively, of the bar next mentioned. Letter M is a bar, adjusted at its centre firmly to the top of standard E; and letters O are ribbons, cords, or ropes, also attached to the ends of bar M in a similar manner with chains K. It is with these ribbons that the sled is guided, for by their use the operator can turn the prow of the rudder in either direction, at will.

The letters S are stirrups or braces in which the operator's feet are placed, and which form a substantial base or fulcrum when putting forth his strength.

What I claim as my invention, and desire to secure by Letters Patent, is—

1. The slotted bar G, in combination with the spring D, when constructed and operating substantially as and for the purposes described.

2. A coasting-sled, having rudder A, bell-holder and bell C, spring E, slot H, chains K, ribbons O, and stirrups S, constructed, arranged, and operating substantially as specified.

EDWARD L. STEVENS.
